UNITED STATES PATENT OFFICE.

JAMES H. L. EAGER, OF BROOKLYN, NEW YORK.

SYRINGE.

1,074,780.

Specification of Letters Patent.

Patented Oct. 7, 1913.

Application filed March 17, 1913. Serial No. 754,825.

To all whom it may concern:

Be it known that I, JAMES H. L. EAGER, a citizen of the United States, residing at Brooklyn, in the county of Kings and State 5 of New York, have invented certain new and useful Improvements in Syringes, of which the following is a specification.

My invention relates to syringes, and more particularly to that class known as water-
10 bag syringes and in which a pressure-seat is used which rests upon the bag, the weight of the person using the syringe causing the wa-
ter or other cleansing fluid to be forced from
such bag and through an injection nozzle to
15 the part to be treated.

In the accompanying drawing illustrating the preferred embodiment of my invention, Figure 1 is a side elevation of my im-
proved syringe, ready for use, Fig. 2 is a
20 vertical section through the syringe nozzle and the support therefor, showing the means for attaching the water tube, and Fig. 3 is a fragmentary bottom plan view of the support for the nozzle, showing the means for at-
25 taching the water tube.

Like letters of reference indicate corresponding parts wherever they occur.

4 designates the usual form of water bag, made of rubber or rubber cloth having a
30 screw threaded filling opening.

5 designates a pressure-seat adapted, as shown, to be placed upon the water bag and provided with a central opening 6 there-
through.

35 Seated upon the face of the pressure-seat and covering the central opening 6 is a dome-
shaped nozzle holder 7 provided interiorly with a screw-threaded portion 8, adapted to receive an injection nozzle 9, having the dis-
40 charge apertures 10^a, which nozzle is prefer-
ably formed from soft rubber. Such nozzle may, however, be of the hard rubber type, in
which case its lower end is provided with a
thread by which it is screwed into place to
45 match that in the nozzle seat.

Extending from the bottom of the down-
wardly extending portion 8 of the nozzle support is a short pipe section 10, closed at
50 its lower end, and provided with a screw
threaded side opening 11, adapted to receive a similarly threaded nipple 12, the opposite end of which fits in the end of a rubber tub-
ing 13, the other end of which tubing is pro-
vided with a screw threaded nozzle adapted
55 to be screwed into the filling opening of the

bag 4. The rubber tubing 13 intermediate its ends is provided with a metal cut-off 14 of the usual construction for this purpose.

15 designates metal tubes, the ends of which are inserted in the rubber tubing and 60 which form desirable connections at the joints of such rubber tubing.

As will be seen from the drawing the pres-
sure-seat 5 is of such size relative to the side
of the water bag 4 as to practically cover 65
the same, so that the person of the user is
prevented from coming in contact with the
hot surface of such bag.

My improved syringe is particularly
adapted for the treatment of the rectum and 70
colon and for the flushing or irrigating of
these parts, and in the particular use there-
of the pressure-seat may be used as a handle
in placing the injection nozzle in position
for use, the water-bag having been previ- 75
ously filled with water or cleansing fluid
and the screw threaded end of the rubber
tubing attached thereto. The pressure-seat
is then placed upon the bag, the patient's
weight thereon causing the water or other 80
cleansing fluid to be gradually expelled from
the bag and through the injection nozzle to
the parts to be treated. The dome-base for
the injection nozzle serves to press upward
the rectum to prevent the escape of water 85
therefrom, as well as a means for housing
the water inlet from the rubber tubing, such
tubing being covered for a portion of its
length and extending under the base, rest-
ing in a groove 16 formed in said base, 90
whereby to house the same and to permit an
even or flush surface of the underside of the
seat 5 on the bag 4, and thereby prevent
rocking of said seat on said bag, and conse-
quent wear of the latter. 95

While I have described my improved
syringe as particularly adapted for the
treatment of the rectum and colon, the same
may be also used as a vaginal douche.

Having thus described my invention what 100
I claim as new and desire to secure by Let-
ters Patent is:

A syringe comprising a water-bag, a pres-
sure-seat consisting of a flat integral mem-
ber of sufficient area relative to the side of 105
the water-bag upon which it is adapted to
be placed to shield the user from contact
with the surface of said bag and having an
opening therethrough, a dome-shaped nozzle
support mounted on said seat over said open- 110

ing and provided with a water-passage therethrough adapted to receive an injector nozzle, and a tube extending beneath said pressure-seat and connected at one end with 5 the water passage through said dome-shaped nozzle support, and having its other end attached to the mouth of the water-bag.

In testimony whereof I affix my signature in presence of two witnesses.

JAMES H. L. EAGER.
